CLAIM

The ornamental design for a tiltroll for adjusting blinds,
as shown and described.

DESCRIPTION

FIG. 1 is a top, front, right side perspective view of a
tiltroll for adjusting blinds showing our new design;
FIG. 2 is a bottom, front, right side perspective view
thereof;
FIG. 3 is a right side elevational view thereof with the
left side being a mirror image thereof;
FIG. 4 is a top plan view thereof;
FIG. 5 is a bottom plan view thereof; and,
FIG. 6 is a front elevational view thereof with the rear
view being a mirror image thereof.

Fig.1.

Fig.2.

Fig.3.
